CLAIM

The ornamental design for a disposable hand operated cartridge body piercing instrument, as shown and described.

DESCRIPTION

FIG. 1 is a perspective view of a disposable hand operated cartridge body piercing instrument, showing the new design; FIG. 2 is a rear lower perspective view thereof; FIG. 3 is a front elevation view thereof, where the rear elevation view is a mirror image of the front elevation view; FIG. 4 is a right elevation view thereof; FIG. 5 is a rear elevation view thereof, where the front elevation view is a mirror image of the rear elevation view; FIG. 6 is a left elevation view thereof; FIG. 7 is a top plan view thereof; and, FIG. 8 is a bottom plan view.

The broken lines shown in FIGS. 1-7 illustrate portions of the disposable hand operated cartridge body piercing instrument that form no part of the claimed design.

1 Claim, 5 Drawing Sheets
